(57) **CLAIM**

The ornamental design for a hole punching assembly, as shown and described.

DESCRIPTION

FIG. 1 is a perspective view of a hole punching assembly in accordance with the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The lines shown in dash-dot-dash represent an indeterminate length and form no part of the claimed design. The broken lines in the drawings depict portions of the hole punching assembly that form no part of the claimed design.
